METHOD AND APPARATUS FOR
REFRIGERATION

William S. Foraker, Zanesville, Ohio

Application November 26, 1932, Serial No. 644,442.

15 Claims. (Cl. 62—105)

My invention relates generally to the art of refrigeration and, more particularly, to an automatic ice machine and refrigerator involving novel methods of freezing and cooling.

The art of refrigeration in general and the design and construction of domestic refrigerating units in particular have been brought to a high state of perfection by developments of recent years. Domestic units, however, are still far from being fully automatic in regard to the manufacture of ice. The present practice requires that freezing trays be manually removed from the unit, filled with water and replaced therein for freezing. The removal of the ice from the trays is another step which involves considerable inconvenience and, on the whole, it may be said that the manufacture of ice in domestic refrigerating units of present design is a matter of considerable annoyance to the average user. A further objection is that the user must examine the trays frequently to see if the ice is fully frozen, if it is desired to manufacture a considerable amount of ice efficiently from the standpoint of the time consumed. These same objections apply to the present commercial ice making machines wherein ice in small cubes is manufactured.

The present domestic refrigerators and commercial ice making machines, such as those above referred to, are further objectionable in that periodically it is necessary to shut off the freezing and cooling apparatus and defrost the same. This is considerable nuisance and renders the refrigeration inoperative for a period of time.

By my invention I provide an apparatus including a novel method of freezing which renders the manufacture of ice in domestic or commercial units of the above described character entirely automatic.

By my invention I also provide novel means for refrigerating the interior of the cabinet of the refrigerator which obviates the necessity of periodically defrosting the refrigerating apparatus. This novel refrigerating apparatus for cooling the cabinet may be used in combination with the automatic freezing apparatus above referred to or may be used independently thereof. Likewise the automatic freezing apparatus and the novel method of freezing may be used independently of the apparatus for refrigerating the cabinet, and in many instances, such as commercial ice making machines of the above referred to character, is generally independently used.

In accordance with my invention, I provide a freezing plate or zone in the refrigerator, and pass a travelling belt carrying ice molds over the plate or through the freezing zone. Automatic means for driving the belt and for filling the molds are provided and the travel of the belt automatically discharges the ice from the molds.

The invention utilizes standard compressing and control equipment and can, therefore, be readily incorporated in present designs of refrigerating units. In addition to the automatic freezing mechanism, I provide means for cooling the interior of the refrigerating cabinet.

For a complete understanding of the invention, reference is made to the accompanying drawings illustrating a present preferred embodiment of the invention, although it is to be understood that numerous changes in construction and operation described may be made without departing from the scope of my broader claims. In the drawings:

Figure 1 is a front elevation, partly broken away, of a domestic refrigerating unit with the invention incorporated therein;

Figure 2 is a partial vertical sectional view taken through the unit on a plane parallel to its rear wall;

Figure 3 is a partial sectional view along the line III—III of Figure 2;

Figure 4 is a partial sectional view taken along the line IV—IV of Figure 3;

Figure 5 is a view showing a detail of the construction illustrated in Figures 3 and 4;

Figure 6 is a sectional view through the unit taken on a plane perpendicular to that of the section of Figure 2 and substantially along the line VI—VI thereof;

Figure 7 is a diagrammatic view illustrating the piping for conducting the refrigerant through the freezing plate;

Figure 8 is a partial front elevation to enlarged scale, with parts in section, of the cabinet cooling coil;

Figure 9 is a sectional view along the line IX—IX of Figure 8;

Figure 10 is a partial plan view of the travelling belt having ice molds formed thereon;

Figure 11 is a diagrammatic view of the circulating system isolated from the remainder of the structure;

Figure 12 is a view partly in section showing a control device for the freezing apparatus;

Figure 13 is a view similar to Figure 12 but at right angles thereto; and

Figure 14 is a circuit diagram of the electric control apparatus for automatically operating the freezing mechanism.

Referring now in detail to the drawings, a 5 domestic refrigerating unit 10 comprises a suitably insulated cabinet 11, a door 12 hinged thereto and a cover 13 for enclosing the compressing and control mechanism. Within the cabinet 11, a storage space 14 is provided with shelves 15. A cooling or chilling coil for the storage space is indicated generally at 16. Apparatus for automatically freezing ice is located in the top of the cabinet and is indicated generally at 17.

15 Referring now to Figure 2, the cabinet 11 has an insulated lid 18 removably supported thereon by a gasket 19 for carrying the refrigerating mechanism proper. The refrigerating apparatus includes a compressor 20 and a float valve 21 for compressing the refrigerant and supplying it to an evaporating chamber 22 (see also Figure 6). The compressor and float valve are of standard construction. A conduit 23 permits vapor to be drawn from the chamber 22 for compression while a conduit 24 delivers liquid refrigerant from the compressor to the chamber under control of the float valve 21.

30 A freezing plate 25 extends over a substantial portion of the inside area of the cabinet adjacent the lid 18. This plate comprises molded insulating material having embedded therein a plurality of coils 26 for circulating refrigerant, and a sheet metal cover which is in intimate contact with the coils. The insulation also extends under the chamber 22 and around a portion of the coil 16. It will be understood that the naturally accumulating frost on the coils may be used as insulation for the coils. The arrangement of the coils 26 with respect to the chamber 22 may best be observed in Figure 7. It will be noted that one end of each of the coils 26 enters the chamber adjacent the bottom thereof while the other end projects upwardly into the chamber. This arrangement, of course, 35 is for the purpose of permitting the introduction of liquid refrigerant into the coils 26 and the removal of refrigerant vapor therefrom.

35 Bearing brackets 27 and 28 depending from the lid 18 support shafts 29 and 30 adjacent the ends of the freezing plate 25. A guiding drum or sheave 31 is mounted on the shaft 29 and a driving sprocket 32 on the shaft 30. A continuous belt 33 having mold forming partitions 34 extends around the drum 31 and the sprocket 32, having suitable holes for engagement with the teeth of the latter. The belt 33 is substantially as wide as the interior of the cabinet 11 is deep. The belt is preferably made of somewhat flexible material. I prefer to use 40 a fabric belt having a rubber top made integral therewith, the rubber top forming the ice cube molds. Figure 10 shows a plan view of a portion of the belt, and Figure 6 shows a transverse section thereof.

45 A ratchet wheel 35 is fixed to the shaft 30 (see Figures 3 and 4). A pinion 36 is rotatable on the shaft 30 and carries a yoke 37 having a pawl 38 cooperating with the ratchet wheel. A rack 39 formed at the lower end of a rod 40 slidable vertically in the lid 18, meshes with the pinion 36. A strip 41 adjustably secured in a recess in the rod 40 has turned out fingers 42 and 43 for engaging with the movable central contact of a switch 44 for a purpose to be described later.

The rod 40 is actuated by an expansible metal

bellows 45. The bellows 45 is adapted to be extended under the pressure of water from any suitable source and tends to return the rod to the position illustrated in Figure 14, upon relief of the pressure which extends it. Water is 5 supplied to the bellows 45 through a conduit 46 connected in any desired manner to a source of water, for example, to a municipal supply. The conduit 46 may extend downwardly through the upper part of the unit and around the chilling 10 or cooling coil 16 for the purpose of pre-cooling it before it enters the molds. It then extends upwardly to a 3-way valve 47 having an operating solenoid 48. As will be apparent from the showing of Figure 2, the plunger of the valve 47, 15 when raised, establishes connection between the two lateral ports thereof, whereas, when it is lowered, it connects the right hand and the bottom ports and cuts off the left hand port from the other ports. A conduit 49 extends through 20 the lid 18 from the bottom port of the valve 47 to a jet pipe 50 extending the depth of the cabinet and having holes for delivering water into a series of aligned individual molds for ice cubes constituting a portion of the belt 33. 25

I shall now describe the automatic operation of the apparatus already disclosed in detail, by reference to Figure 2 for the structure and to Figure 14 for the circuits and control devices. The auxiliary control devices will be mentioned 30 during the description of the operation.

In describing the operation of the automatic freezing and delivering mechanism, it will be assumed that the parts are in normal inoperative position. In Figures 2 and 4 the rod 40 is 35 in an intermediate position of its upward stroke while in Figure 14 it is shown at the upper end of the stroke.

When it is desired to start the automatic operation of the freezing and delivering mechanism, a switch 51, normally held open, is closed by turning a knob 52 on the front of the cover 13. The knob is connected by a friction clutch 52a to a ratchet wheel 54 rotatable on the knob shaft. Rotation of the knob shaft in the proper 40 direction moves a finger 56 out of engagement with the moving contact of the switch 51. The latter thereby completes a circuit from a current source, indicated as a battery 57, for the solenoid 50 45 of the valve 47. The circuit for the solenoid 50 50 is completed through a back contact 58 of a resetting relay 59. The angle through which the knob 52 is turned determines the amount of ice which will be delivered by the apparatus before it automatically stops. The knob is gradually reset, by means to be explained shortly, and the return of the finger 56 subsequently opens the switch 51 to suspend further automatic operation of the delivery mechanism.

The energization of the solenoid 48 raises the 60 plunger of the valve 47. As previously explained, this closes the bottom port of the valve and connects two lateral ports whereby water under the pressure maintained in the conduit 46 flows through the valve into the bellows 45. Incidentally, the water flowing through the valve is cooled because the conduit 46 for a considerable portion of its length is in close proximity to the cooling coil 16. The admission of water under pressure to the bellows 45 causes the latter to expand and push the rod 40 downward. The downward movement of the rod 40, through the rack 39 and the pinion 36, in cooperation with the pawl 38 and the ratchet wheel 35, turns the shaft 30 and advances the belt 33 a 75

distance equal to the center to center spacing of the molds formed therein. As the rod 40 reaches the lower limit of its movement, the upper finger 42 on the strip 41 carried thereby engages the moving contact of the switch 44 to cause it to engage the bottom contact and complete a circuit therethrough from the battery 51 and through the switch 51 to the resetting relay 59. The energization of the relay 59 opens the circuit for the solenoid 48 and permits the plunger of the valve 47 to drop. The armature of the relay 59 when operated, is latched up by the armature of an unlatching relay 60. The closing of the front contact 61 of the relay 59 completes a circuit for the solenoid 62 having an operating pawl 65 engaging the ratchet wheel 54 to reset the latter and its shaft one step. The solenoid 62 remains energized and the pawl 65 is elevated until the unlatching relay 60 is energized.

When the plunger of the valve 47 drops, the closing tendency of the bellows 45 forces water therefrom through the valve into the conduit 49 and the pipe 50 which delivers the required amount of water to each of a series of molds across the width of the belt 33.

The raising of the rod 40 causes the bottom finger 43 of the strip 41 to engage the moving contact of the switch 44 and move it into engagement with the upper contact to complete a circuit through the switch 51 for the unlatching relay 60. This circuit includes alternatively, a manual switch 63 or an automatic switch 64. The freeze switch 64 is closed by the expansion of the water in freezing to ice. The switch extends downwardly from the lid 18 between adjacent columns of molds, as shown in Figures 2 and 14. If it is assumed that the device is being placed in operation for the first time, the molds preceding those filled with water on the first operation will be empty and the freeze switch 64, therefore, will not be closed. In the starting period, therefore, the switch 63 must be manually closed for a short time. The relay 60, when energized, releases the armature of the relay 59 and breaks the circuit for the magnet 62. The pawl 65 then drops to re-engage the ratchet wheel 54 for the next resetting step. The operation of the unlatching relay re-establishes the circuit for the magnet 48 through the back contact 58 of the relay 59 and the switch 51.

The operating cycle above described is then repeated a sufficient number of times to charge a number of the transverse rows of molds on the belt 33 with water. When the required number of molds have been filled with water, the switch 63 is opened. As an alternative, the switch 63 may be left closed during the starting period and the knob 52 set so that only the required number of molds will be filled with water before suspending the preliminary operation. It will be obvious that the continued resetting of the ratchet wheel 54 by the solenoid 62 eventually opens the circuit for the magnet 48 at the switch 51, after which the operation of the system is precluded.

Under either of the above conditions, the switch 63 is opened after the preliminary operation to fill the first few molds. When the water in the molds first filled freezes into ice, the switch 64 closes. A final operation of the unlatching relay 60 then takes place if it has not already been effected by leaving the switch 63 closed. The water in the molds thus filled is

then frozen. The freezing period is comparatively short, because of the intimate contact of the molds with the freezing plate.

When the water in the initially charged molds has been frozen, further operation of the mechanism may be caused by again turning the knob 52 and completing the circuit through the switch 51. Since the switch 63 has been opened after the filling operation and remains open, the operation of the mechanism will only take place 10 after the knob 52 has been turned and when cubes have been frozen and are ready to be discharged. If the cubes in the molds adjacent the switch 64 are not frozen, the switch will remain open and the operation of the apparatus 15 automatically interrupted until freezing has taken place, at which time operation will automatically commence if the switch 51 remains closed. Thus, cubes will be discharged, if desired, immediately upon freezing and repeated 20 examination of the trays or molds to determine when the cubes are frozen eliminated. When the cubes are frozen the switch 64 is automatically closed and cubes may be automatically obtained by merely turning the knob to indicate 25 the number of cubes desired. This number will be delivered and the apparatus will automatically stop and no more will be delivered until the knob 52 is again turned. It will be apparent that the operations, once the molds 30 have been filled, will be absolutely automatic and turning of the knob 52 the only operation necessary in order to obtain any desired number of cubes. The knob 52 may have a pointer thereon and a dial adjacent thereto to indicate 35 the amount the knob is to be turned to obtain a given number of cubes.

The usual knob for controlling the temperature of the cabinet may also be provided as shown in Figure 1.

As will be apparent from the showing of Figure 2, the end walls of the ice cube molds are distorted as they pass around the drum 32. This facilitates the discharge of the cubes from the traveling belt. An up-turned portion 66 of the 45 lining of the cabinet 11 engages the ice cubes to force them from the molds. The cabinet being adjacent the discharge end is curved to engage one edge of the cubes being discharged to facilitate the discharging operation by effecting a 50 leverage action on the cubes. The successive positions of the cubes as they are discharged from the molds are illustrated in dotted lines in Figure 2. A suitable receptacle may be placed in the upper portion of the cabinet 10 to receive 55 the cubes as they are discharged, if desired.

The cooling unit for the cabinet proper is best illustrated in Figures 1, 8, 9 and 11. The lining of the cabinet 11 is curved outwardly from the back wall thereof to form a chamber 68 for the 60 cabinet cooling unit. Holes 69 in the chamber permit circulation of air therethrough. The chamber 68 has a brine tank 70 therein to give an increased cooling surface. It will be understood, of course, that any other suitable apparatus may be substituted for the brine tank to give increased radiation surface. The tank 70 has a corrugated outer surface 71 for the purpose of increasing its surface area. The tank 70 is traversed by the cooling coil 16 already referred to. One end of the coil 16 projects upwardly into the vaporizing chamber 22 as shown in Figure 6 but terminates below the level of the liquid refrigerant therein. The other end of the coil, as shown in Figures 1 and 2, extends above 75

the level of the liquid in the chamber. In this way a continuous supply of liquid refrigerant to the cooling coil 16 is insured and the vaporization of the liquid in the coil absorbs the heat from the contents of the cabinet. The vapor formed in the coil is removed by the compressor unit which communicates with the vaporizing chamber 22.

In the bottom of the chamber 68 a sump 72 is provided for collecting any condensate forming on the cabinet cooling unit. Troughs 73 disposed beneath portions of the water conduit 46 deliver any moisture condensing thereon to the sump. The water conduit 46 includes a Venturi section 74 having an inlet port controlled by a ball valve 75. The ball valve is adapted to be opened by the suction created by water flowing through the venturi. The water flowing through the venturi also draws the condensate from the sump into the water line until the valve 75 is closed by cessation of flow through the line 46.

The operation of the compressor 20 is controlled in accordance with the temperature of the brine tank in the cabinet 11. The temperature of the tank, of course, is controlled by the temperature of the cabinet. A tube 76 terminating on top of the brine tank 70 contains an expansible liquid and communicates with a metallic bellows 77. Upon a predetermined rise in the temperature of the exterior of the brine tank, the liquid in the tube 76 expands to operate the bellows 77 and close a switch 78 for starting the compressor motor. When the temperature of the tank has been sufficiently lowered, the inherent retractive effect of the bellows opens the switch upon suitable contraction of the thermally responsive liquid in the tube 76.

A suitable temperature differential between the brine tank and the freezing plate or zone will be maintained. This differential will be determined by relative areas and circulation of air thereover. This permits the use of a single vaporizing chamber for both the brine tank and freezing plate or zone. When the temperature of the tank reaches its predetermined highest temperature, the switch 78 will be closed and the compressor started. This predetermined temperature will be sufficiently high to permit defrosting of the cooling apparatus, thus giving a defrosting cycle which eliminates the necessity of shutting down the refrigerator to defrost the apparatus. Due to the temperature differential between the brine tank and the freezing plate or zone, the temperature in the latter will always be sufficiently low to cause freezing, and temperature control of both the tank and the freezing plate or zone effected by one apparatus.

Holes 81 may be provided in the top lining of the cabinet to permit limited circulation of air around the freezing apparatus to prevent contamination or collection of food odors which might affect the quality of the ice cubes.

It will be apparent from the foregoing explanation of the invention that it provides for the manufacture of any desired number of ice cubes in the ordinary domestic or commercial ice making refrigerator under automatic control. The invention is particularly adaptable to domestic refrigerators as designed at present, but also has a further field of usefulness in small automatic ice making machines for domestic or other purposes. The ice making apparatus, obviously, may be employed independently of the cooling cabinet of the ordinary domestic refrig-

erator. General advantages of the invention such as certainty of operation, simplicity of control and the fact that the operation is entirely automatic, will be apparent without further mention.

Although I have illustrated and described herein but a single present preferred embodiment of the invention, it will be clear that numerous changes in the embodiment described may be made without departing from the spirit of the invention or the scope of the appended claims.

I claim:

1. Ice making apparatus comprising a freezing zone, means for circulating refrigerant therethrough, a mold movable through said zone, an expandable chamber for moving said mold, and a valve for admitting fluid under pressure to said chamber, said chamber being effective to discharge its exhaust fluid through said valve into said mold.

2. Ice making apparatus comprising a freezing zone, a mold-carrying belt traversing said zone, a hydraulic motor for advancing said belt, and a valve for admitting water to said motor to operate the belt and for delivering the water exhausted from the motor to a mold on said belt.

3. Ice making apparatus comprising a freezing zone, a mold adapted to travel thereacross, a hydraulic motor which advances said mold, a valve for admitting water to the motor and delivering the water exhausted from the motor to said mold, and means operated by said motor for controlling said valve.

4. In an ice making apparatus, the combination with a freezing plate, a mold movable thereacross, automatic means for moving the mold across the plate and filling it with water, means operated by the mold moving means for causing a repetition of the moving and filling cycle, and means actuated by the freezing of the water in the mold for causing continued operation of said filling and moving means.

5. In a refrigerator, a storage cabinet, a cooling coil therefor, a freezing zone, a continuous mold movable therethrough, and automatic means including a dial switch for moving the mold and charging it with water.

6. Refrigerating apparatus comprising a continuous belt, molds carried thereon, and means for automatically charging the molds with water and moving them across the freezing plate including a control valve and a hydraulic motor, and means controlled by said motor for suspending operation of the valve after a predetermined number of operations thereof.

7. In a refrigerating apparatus, the combination with a freezing zone, a mold movable therewith, and means for filling and moving said molds, of means including an electrically actuated relay controlled by the mold moving means for preventing further operation thereof.

8. In a refrigerating apparatus, the combination with a freezing zone, a mold movable therethrough, and means for filling and moving the mold, of means including an electrically actuated relay for preventing operation of said last-mentioned means after a selected number of operations thereof.

9. In a refrigerating device, the combination with a freezing zone, and a continuous mold-carrying belt extending therethrough, of a self-retracting hydraulic motor and a uni-directional drive actuated thereby for advancing said belt.

10. In a refrigerating device, the combination with a freezing zone, and a continuous mold-

carrying belt extending therethrough, of a self-retracting hydraulic motor, a uni-directional drive actuated thereby for advancing said belt, and a valve for controlling the admission of fluid 5 under pressure to the motor and effective to divert the exhaust therefrom to the molds on said belt.

11. In a refrigerating device, the combination with a continuous mold-carrying belt, a uni-directional drive therefor and a self-retracting hydraulic motor for actuating the drive, of a valve effective in one position to connect the motor to a source of water pressure and, in the other, to deliver water from the motor to the 10 molds of said belt and electromagnetic means to operate said valve.

12. Ice making apparatus comprising a freezing plate, a mold, means including a hydraulic motor for moving the mold over said plate in a 15 step-by-step manner, and means controlled by said motor for supplying water to said mold.

13. In a refrigerating device, a continuous mold carrying belt, means for supplying water to the molds on the belt, means for freezing the water in the molds, and electrically actuated means including a motor and control system 5 therefor for moving the belt past said freezing apparatus in a step-by-step manner.

14. Ice making apparatus comprising a freezing zone, a mold movable through said zone, and electrically actuated means including a valve, a 10 dial switch and a motor element for supplying water to said mold and for moving the mold through said zone.

15. Ice making apparatus comprising a continuous mold carrying belt, freezing apparatus, 15 and electrically actuated means including a dial switch and a motor element for moving said belt past said freezing apparatus and for substantially simultaneously supplying water to the molds on the belt.

WILLIAM S. FORAKER.

20
